UNITED STATES PATENT OFFICE.

JOHN B. LARSON, OF MINNEAPOLIS, MINNESOTA, ASSIGNOR OF ONE-FOURTH TO EMIL T. ENGSTROM AND ONE-FOURTH TO WILLIAM M. HIGLEY, BOTH OF MINNEAPOLIS, MINNESOTA, AND ONE-FOURTH TO JNO. B. LEE COMPANY, A CORPORATION OF MINNESOTA.

TRAY FOR GAS-PURIFYING TANKS.

1,033,809.

Specification of Letters Patent. Patented July 30, 1912.

Application filed March 30, 1911. Serial No. 617,881.

To all whom it may concern:

Be it known that I, JOHN B. LARSON, a citizen of the United States, residing at Minneapolis, in the county of Hennepin and State of Minnesota, have invented certain new and useful Improvements in Trays for Gas-Purifying Tanks; and I do hereby declare the following to be a full, clear, and exact description of the invention, such as will enable others skilled in the art to which it appertains to make and use the same.

My invention has for its object to provide an improved tray adapted for use to support fibrous or porous filtering material within gas purifying tanks or boxes and, to this end, the invention consists of the novel devices and combinations of devices herein-after described and defined in the claims.

In the accompanying drawings, which illustrate my invention, like characters indicate like parts throughout the several views.

Referring to the drawing, Figure 1 is a view partly in side elevation and partly in vertical section taken through a gas purifying tank and showing my improved trays applied therein; Fig. 2 is a plan view, with parts broken away, illustrating the construction of the improved tray; Fig. 3 is a vertical section taken on the irregular line $x^3 x^3$ of Fig. 2; Fig. 4 is an enlarged transverse section taken on the line $x^4 x^4$ of Fig. 2; and Fig. 5 is an enlarged transverse section taken on the line $x^5 x^5$ of Fig. 2.

The gas purifying tank or box 1 is of the usual or any suitable construction and may be either round or rectangular in cross section. It is shown as provided with a detachable cover 2 secured thereto with a gas tight joint, by bolts or any other suitable devices, not shown. The gas is delivered into the bottom of the tank through a supply pipe 3 and is drawn from the top of the said tank through a gas out-let pipe 4, which, as shown, is extended down through the bottom of the tank. In the construction illustrated, the tank is divided into three vertical compartments by two of my improved trays, each of which trays is independently supported on laterally spaced horizontal transverse beams 5, the ends of which are secured to the sides of the said tank.

Both of the trays are or may be identical in construction and the description of one

thereof will answer for the description of both. The tray is made up of a multiplicity of horizontally disposed and horizontally spaced parallel wooden strips 6 and 7, and transverse spacing and supporting cleats 8 and 9. The lower wooden cleats 8 rest directly upon the fixed supporting bars 5 while the upper wooden cleats 9 are interposed between the lower strips or boards 6 and the upper strips or boards 7. Said boards 6 and 7, it will be noted, are staggered in respect to each other, so that the gas, in passing upward through the tray, will take a zig-zag course, as indicated by arrows marked on Fig. 5. Certain of the cleats of the lower cleats 8, to-wit, as shown, 70 alternate members, are provided with rigidly secured upwardly projecting wooden dowel pins 10 and 11, the former of which project above the cleats 8 into which they are inserted, preferably, about three times as 75 far as the relatively short dowel pins 11. These long and short dowel pins are alternated. The short dowel pins 11 are adapted to engage coöperating half seats or semi-circular notches formed in the abutting ends 80 of the lower boards 6. The long dowel pins 10 project upward through perforations in the upper spacing cleats 9 and their upper ends engage with coöperating half seats or semi-circular notches formed in the abutting 85 ends of the upper boards 7. This arrangement, as is obvious, affords simple and efficient means for detachably connecting the component members of the tray without the use of either nails or bolts. Hitherto, the 90 parts of the tray have usually been connected either by nails or by bolts which can be applied and removed by considerable work and, furthermore, these metallic parts, under the chemical action due to contact therewith 95 of the gas in purifying material supported on the tray, rapidly corrode.

In building up the improved tray, the lower cleats 8 are first laid upon the supporting beams 5. Then the lower boards 6 100 are laid thereon with their notched ends properly engaged with their short dowel pins 11. Then the upper spacing cleats 9 are applied on top of the boards 6, as shown, with the perforated members thereof being 105 slipped over the long dowel pins 10. Then, and finally, the upper boards 7 are laid with their notched ends properly engaged with

the upper ends of the said long dowel pins 10. When the tray is to be taken apart for cleaning or for other purposes, the above described order of assembling the parts 5 thereof is reversed.

In Fig. 1, the filtering and purifying material, usually made up of wooden shavings and iron shavings, and certain other elements, is indicated by the character Y. 10 10 This purifying or filtering material has nothing to do with my present invention which relates only to the improved tray for supporting the filtering material in such manner that the gas will find free passage 15 through the entire body thereof.

What I claim is:

1. A tray for gas purifying tanks made up of upper and lower transverse supporting and spacing cleats, certain of the said lower 20 cleats having upwardly projecting relatively long and relatively short dowel pins, and lower and upper overlapped boards, the latter being placed upon the said lower cleats and having end notches engaging the said short dowel pins, and the upper boards being placed upon the upper cleats and having notched ends engaging the upper ends of said long dowel pins. 25
2. In a tray for gas purifying tanks, the 30 combination with lower and upper trans-

verse cleats, the former having alternated relatively short and long dowel pins, and the said upper cleats having perforations through which the said long dowel pins are passed, overlapped lower and upper boards, 35 the former being interposed between the said upper and lower cleats and having end notches that engage the said short dowel pins and the said upper boards being placed upon the said upper cleats and having end 40 notches that engage the upper ends of said long dowel pins, substantially as described.

3. A tray for gas purifying tanks made up of upper and lower transverse supporting and spacing cleats, certain of the said lower 45 cleats having upwardly projecting dowel pins, and lower and upper boards in staggered arrangement, the latter being placed upon the lower cleats and having end notches engaging certain of the said dowel 50 pins, and the upper boards being placed upon the upper cleats and having notched ends engaging certain of the said dowel pins, substantially as described.

In testimony whereof I affix my signature 55 in presence of two witnesses.

JOHN B. LARSON.
